UNITED STATES PATENT OFFICE.

JOHN EDGAR MYERS, OF STEUBENVILLE, OHIO.

WARNING-SIGNAL.

1,316,318.

Specification of Letters Patent. Patented Sept. 16, 1919.

Application filed July 27, 1918. Serial No. 247,004.

To all whom it may concern:

Be it known that I, JOHN EDGAR MYERS, a citizen of the United States of America, and resident of Steubenville, county of Jefferson, State of Ohio, have invented certain new and useful Improvements in Warning-Signals, of which the following is a specification.

This invention relates broadly to danger or warning signals, and more specifically to a device whereby danger points in a roadway may be indicated to drivers of lighted vehicles.

The primary object of the invention is to provide a device adapted for mounting at danger points along a roadway in position for receiving light rays projected from the lamps of approaching automobiles or other vehicles and designed to color and reflect rays impinging thereon to visually indicate to the drivers of such vehicles the presence of danger at or near such point.

A further object of the invention is to provide a lightless color signal whereby drivers of lighted vehicles may be visually warned of the presence of a danger point in a roadway with practically the same effect as if a lighted lamp of the same color were employed at such point.

In describing the invention in detail, reference is herein had to the accompanying drawings, in which—

Figure 1 is a front elevation of the colored glass light reflector which constitutes an essential feature of the invention;

Fig. 2 is a partial vertical sectional view of the invention; and—

Fig. 3 is a reduced front elevation of the invention mounted upon a post.

Referring to said drawings, in which like designating characters distinguish like parts throughout the several views—

A indicates generally a hollow circular blown glass reflector having a concave front or reflecting face 1 and having a convex back 2 disposed rearward of said face, as shown in Fig. 2. The glass of which said reflector is composed may be of any preferred color, but is preferably ruby red to indicate danger, or green to indicate that caution should be observed. The interior or rear surface of the face 1 of the reflector is coated with quicksilver which is introduced through the neck 3 that is integrally carried by the back 2 in a central position, said neck being retained following the

blowing operation. After the introduction of the quicksilver or other coating employed for rendering the glass effective as a reflector, the neck 3 is hermetically sealed to prevent access of moisture which would otherwise cause the coating to deteriorate rapidly and thus destroy the efficiency of the device as a reflector.

Owing to the more or less fragile character of the reflector, the same is preferably mounted within an inclosing frame or casing 4 whereby it is shielded against injury, such casing being provided with a clear glass front 5 through which light rays may pass unobstructedly. Said casing may be of any preferred form adapted for mounting upon a post 6 or other convenient support, the casing herein shown for illustrative purposes being of plain box-like form and having a socketed member 7 attached interiorly to the back thereof, said member being adapted to have the neck 3 of the reflector seat snugly in the socket thereof for supporting said reflector.

The invention is designed for mounting in suitable position at or adjacent to points of danger in a roadway, as at dangerous turns, crossings, and the like, where the face of the reflector will receive rays of light projected from the lamps of approaching cars and directly return such rays by reflection and in the color of the glass as a warning to the drivers of such cars. Concentrated beams or shafts of light of great brilliance and of the color of the glass are returned by the face of the reflector, the appearance and effect being substantially the same as that of a lighted signal lamp with a colored lens located at the same point.

The invention is also adapted for use as a warning signal on horse-drawn or other road vehicles and obviously may take the place of the usual tail lamp on automobiles.

As is apparent, various advantages are possessed by the invention described, among which may be mentioned simplicity, cheapness, effectiveness, durability, and absence of upkeep cost.

As used throughout the specification and claims the term "reflector" is applied to the colored glass part and does not include the coating.

What is claimed is—

1. A signal of the character described, comprising a hollow blown reflector of colored glass having an interior coating of

quicksilver and hermetically sealed, said reflector having a concave reflecting surface.

2. A signal of the character described, comprising a hollow reflector of colored glass having a concave reflecting surface, said reflector being silvered interiorly and being closed to prevent access of moisture to its interior.

3. A signal of the character described, comprising a hollow blown reflector of colored glass having a concave reflecting surface, said reflector being silvered interiorly and having a hermetically sealed neck disposed centrally of the back thereof, and a casing inclosing said reflector, said casing having a transparent glass face.

4. A signal of the character described,

comprising a hollow blown reflector of colored glass having a concave reflecting surface, said reflector being silvered interiorly and having a hermetically sealed neck disposed centrally of the back thereof, and a casing for said reflector, said casing having a portion in which the neck of said reflector is seated for supporting the latter, and having a transparent glass face in front of said reflecting surface. 20 25

In testimony whereof I affix my signature in presence of two subscribing witnesses.

JOHN EDGAR MYERS.
